Primary Examiner — Prabhakar Deshmukh(74) *Attorney, Agent, or Firm* — Thomas M. Freiburger(57) **CLAIM**

The ornamental design for a recess mount electronic cam lock, substantially as shown and described.

DESCRIPTION

FIG. 1 is a front left perspective view of a recess mount electronic cam lock according to our new design;

FIG. 2 is a top plan view thereof;

FIG. 3 is a left side view thereof;

FIG. 4 is a front elevation view thereof;

FIG. 5 is a right side view thereof; and,

FIG. 6 is a bottom plan view thereof.

The broken lines indicate unclaimed portions and form no part of the claimed design. The rear side disclaimed.
